US00D972529S

(12) **United States Design Patent** (10) **Patent No.:** **US D972,529 S**
(45) **Date of Patent:** **** Dec. 13, 2022**

(54) **HEADPHONES**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/835,626**

(22) Filed: **Apr. 20, 2022**

Related U.S. Application Data

(63) Continuation of application No. 29/818,005, filed on Dec. 6, 2021, which is a continuation of application

(57) **CLAIM**

The ornamental design for headphones, as shown and described.

DESCRIPTION

The patent or application file contains at least one drawing executed in color. Copies of this patent or patent application publication with color drawing(s) will be provided by the Office upon request and payment of the necessary fee.

U.S. Design application Ser. No. 29/731,847, filed on Apr. 17, 2020, is also incorporated herein in its entirety by reference thereto.

FIG. 1 is a top front perspective view of headphones showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
FIG. 8 is a bottom view thereof.

**1 Claim, 7 Drawing Sheets
(7 of 7 Drawing Sheet(s) Filed in Color)**

Related U.S. Application Data

No. 29/779,423, filed on Apr. 19, 2021, now Pat. No. Des. 937,806, which is a continuation of application No. 29/731,849, filed on Apr. 17, 2020, now Pat. No. Des. 916,680.
